POLE

Alan E. Brickman, New Haven, Conn., assignor to
 The American Steel and Wire Company of New
 Jersey, a corporation of New Jersey

Application January 8, 1943, Serial No. 471,756

7 Claims. (Cl. 189—29)

The present invention relates to improved means for strengthening a supporting pole in the region of the ground line.

One object of the invention is to provide a supporting pole including a detachable base portion, to facilitate the initial installation of the pole as well as its withdrawal for reuse at a different location.

The invention will be more fully apparent from the following detailed disclosure and appended claims when read in connection with the accompanying drawing, in which:

Figure 1 is a view showing the lower end of the pole, to illustrate the means for augmenting the strength of the pole in the vicinity of the ground line.

Figure 2 is an elevation viewed from the left of Figure 1.

Figure 3 is a view of a wooden filler used at the lower end of the pole.

Figures 4 and 5 are plan and side views respectively of Figure 3.

Figure 6 is a transverse section on line 6—6 of Figure 1.

Referring in detail to the drawing, Figures 1 and 2 illustrate means for augmenting the strength of the pole 10 in the vicinity of the ground line 12. The pole is made of rolled or pressed steel of light gauge, substantially channel shape in cross section, as shown in Figure 6, and includes oppositely inclined side flanges 14 and 16 connected by a central web 18, the flanges having outturned wings 22 and 24 at their outer extremities.

Coating with the lower end of the pole 10 is a relatively short anchorage post 25 which is substantially of the same cross-sectional shape as the pole 10. The extreme outer wings 26 and 28 of this anchorage post are adapted to lie substantially parallel to the wings 22—24 of the pole 10. As thus arranged, the two members 10 and 25 will jointly define a longitudinally extending cavity or chamber between them. This cavity preferably has inserted therein a creosoted wooden filler block 30 of the cross-sectional shape shown in Figure 4, so as to make a neat fit between the converging side flanges of the pole 10 and post 24. The members 10, 25 and 30 are detachably secured together as a unit by means of a through-bolt 32.

It is deemed important to provide means for holding the metallic channel-like pole 10 and post 25 in slightly spaced relationship, and this relationship is assured during driving of the poles, by provision of projections 34 either extruded or

struck up from the wings of the pole or the post. This spaced relationship of the component parts of the assembled structure provides desirable strength values, as well as fatigue distribution, and insures an adequate means for providing ventilation between the pole and post which desirably retards corrosion of the metal parts. The post 25 preferably has secured near its lower extremity an anchor plate 36 whose lower edges 38 preferably converge so as to form a point to facilitate driving.

The base construction of the pole described is an improvement over conventional forms of metal posts or poles, which experience teaches frequently break at the ground line. In prior art constructions, such break-off is most frequent in frozen ground, due in part to the pole's vibration and the difference in ductility of the metal fibers above and below the ground level. A common and serious condition which exists in prior art poles is that in periods of extreme cold weather, the portion of the pole above ground is exposed to the elements, while the embedded portion is protected somewhat by the warmth of the earth. Thus there is a temperature differential in different parts which results in an inherent weakness in the region of the ground line. By provision of the anchorage post reinforced by the wooden filler block above described, this inherent weakness in prior art posts is overcome and thus the useful life of a pole of light gauge metal is materially increased.

From the foregoing, it is also apparent that the invention provides an improved type of pole, which is effectively reinforced in the vicinity of the region of the ground line, where prior metal poles have been inherently weak and subject to failure. The anchor post-like member or component of the pole used in the region where it enters the ground, is of such design and arrangement that the parts can be quickly and easily installed and assembled in working position. Thus in the event of floods or windstorms, they can be readily set up so as to provide necessary utilities. Because of the inherent features of construction, after the emergency passes the parts can be readily dismantled for reuse in other localities.

While I have described quite precisely certain preferred structural details of the embodiments of the invention herein illustrated, it is to be understood that I am not limited thereto except where the claims recite specific structure, since various modifications and substitutions of equivalents may be made by those skilled in the art

without departure from the invention as defined in the appended claims.

I claim:

1. A pole of the character described, comprising an upright metal member of channel shape in cross section, a metallic channel-shaped anchorage member positioned adjacent the lower end of the pole and adapted to be embedded in the ground, the channels of the pole and the anchorage member facing one another, and a non-metallic filler block fitting the channels of said members and rigidly secured thereto.

2. A pole of the character described, comprising an upright metal member of channel shape in cross section, a metallic channel-shaped anchorage member positioned adjacent the lower end of the pole member and adapted to be embedded in the ground, the channels of the pole and the anchorage member facing one another, a non-metallic filler block fitting the channels of said members, and means for detachably securing all of the aforesaid parts in assembled relationship.

3. A pole of the character described, comprising a metallic member having diverging side flanges connected by a web, the said side flanges having outwardly directed wing portions substantially parallel to the plane of the said web, a metallic anchorage member of approximately the same cross-sectional contour as the specified pole member, the outturned wings of the flanges of both members being disposed closely adjacent to one another, and a non-metallic filler block located above ground engaging the webs and flanges of the pole member and anchorage member, said filler block being detachably secured to said members by a fastening element penetrating them.

4. A pole of the character described, comprising a metallic member having diverging side flanges connected by a web, the said side flanges having outwardly directed wing portions sub-

stantially parallel to the plane of the said web, a metallic anchorage member of approximately the same cross-sectional contour as the specified post member, the wings of the flanges of both members being disposed closely adjacent to one another, a wood filler engaging the webs and flanges of the pole member and anchorage member, and means detachably securing the said three component parts in assembled relationship.

5. A pole of the character described, comprising a metallic member having diverging side flanges connected by a central web flange, the said side flanges having outwardly directed wing portions substantially parallel to the plane of the said web, a metallic anchorage member of approximately the same cross-sectional contour as the pole member, the outturned wings of both members being disposed closely adjacent to one another, a non-metallic filler engaging the webs and flanges of the post member and anchorage member, and spacer protrusions formed on the wings of one of said members so as to determine the spaced relation between them.

6. A pole of the character described, comprising a metallic member having upright side flanges forming a trough in cross section, a metallic anchorage member also having upright side flanges forming a trough in cross section, a non-metallic filler block embraced by the flanges of both said members, and means securing the three component parts in assembled relationship.

7. A pole of the character described, comprising a metallic member having diverging upright side flanges, a metallic anchorage member also having diverging upright side flanges, a wooden filler embraced by the diverging flanges of both members, and means securing the said three component parts in assembled relationship.

ALAN E. BRICKMAN.
